CLAIM

The ornamental design for a garden shear, as shown and described.

DESCRIPTION

FIG. 1 is a perspective view of a garden shear showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof showing the area upon which a zoom-in view taken and shown in FIG. 9;

FIG. 9 is a zoom-in view thereof;

FIG. 10 is a right side view thereof showing the area upon which a zoom-in view taken and shown in FIG. 11;

FIG. 11 is a zoom-in view thereof;

FIG. 12 is an embodiment showing my design for the garden shear in use; and,

FIG. 13 is another embodiment showing my design for the garden shear in use.

The broken line is for the purpose of illustrating environment structure and forms no part of the claimed design.
